UNITED STATES PATENT OFFICE

2,508,210

SEMAUTOMATIC OVAL CIGARETTE FEED

Charles Arelt, Richmond Hill, N. Y., assignor to
American Machine & Foundry Company, a corporation of New Jersey

Application March 7, 1945, Serial No. 581,426

7 Claims. (Cl. 226—5)

1

This invention relates to cigarette packaging machines, more particularly to the construction of a cigarette feed containing a supply of cigarettes and equipped with an ejector for delivering cigarettes from the cigarette feed into a cigarette box positioned to receive the ejected cigarettes.

Heretofore oval cigarettes were packaged by girls who manually inserted them into cigarette boxes. The total daily production of a girl seldom exceeds 30,000 oval cigarettes. Therefore a great deal of labor was required to meet the production requirements of even a moderate sized cigarette factory. With the construction exemplified herein a daily production of 75,000 oval cigarettes per machine has been obtained in one cigarette factory. Accordingly, a considerable saving in labor has been effected with the construction of my machine. For this purpose a supply of cigarettes is maintained in the cigarette feed from which a row or layer containing any suitable number of cigarettes such as 10 is ejected into the cigarette box. Then a second layer of cigarettes is ejected to fill the box, and the box is closed.

One of the main objects of the invention is to provide operating mechanism for the ejector which will be set into operation by a cigarette box positioned to receive cigarettes delivered from the cigarette feed. For this purpose the ejector may be yieldingly urged into position to eject the cigarettes and this movement of the ejector is normally prevented by a latch engaging the ejector. A feeler, which is connected to the latch, is provided in front of the cigarette feed to be tripped by a cigarette box positioned to receive the ejected cigarettes and thus disengage the latch from the ejector and permit ejection of cigarettes into the cigarette box. Preferably the ejector is operated by a cam lever provided with a cam follower engaging a continuously revolving cam. Thus, when the latch is disengaged from the ejector, the cam lever will operate the ejector.

Another object of the invention is to permit oval cigarettes to be fed downwardly from the hopper without clogging into positions from which they are ejected into the cigarette box. To this end, below the hopper there are provided spaced vanes providing passageways into which cigarettes are guided from the hopper to the bottom of the passageways, and the vanes are vibrated to assure the proper feeding of cigarettes into the passageways.

With these and other objects not specifically mentioned in view the invention consists in cer-

2

tain constructions and combinations hereinafter described.

In the accompanying drawings which form a part of this specification and in which like characters of reference indicate the same or like parts:

Fig. 1 is a front elevation of a cigarette feed exemplifying the invention, the forward portion of the table being shown in section and certain parts being omitted;

Fig. 2 is a sectional view of the same taken on the line 2—2 of Fig. 3, the cigarette hopper being shown in section;

Fig. 3 is a sectional view of the improved cigarette feed taken on line 3—3 of Fig. 2, the table being omitted from this view; and

Fig. 4 is a detail view on a reduced scale of the cigarette feed viewed from line 4—4 of Fig. 3.

Referring to the drawings, it will be seen that on a table 10 are located upright blocks 12 and 14 upon whose upper ends are supported strips 15 and 16. Bolts 17 and 18 passing through table 10 secure the blocks 12, 14 and strips 15, 16 in position on the table. A pair of strips 19, whose ends rest on blocks 12 and 14, are detachably secured to the ends of strips 15 and 16 by screws 20. The lower edges of the rear and front walls 21, 22 of the cigarette hopper rest on the upper edges of the strips 19. The front wall 22 is fastened to the front edges of the side walls 24 of the hopper and the front ends of strips 15 and 16 by screws 25, and the rear wall 21 is similarly fastened to the rear edges of the side walls 24 of the hopper and the rear ends of strips 15 and 16. The front wall 22 may be provided with an opening 26, which is closed with glass, to permit the contents of the hopper to be inspected.

Table 10 is provided with a central opening extending from the proximity of the rear end thereof to the forward end thereof, this opening being of suitable shape to accommodate various parts hereinafter described. On a base plate 30, which is suitably secured to table 10 and has a portion extending forwardly between the blocks

45 12 and 14, is fastened by screws 31 (Fig. 2), a plate 32. Plate 32 extends rearwardly from the forward edge of plate 30 to a point underlying the rear wall 21 of the hopper. Brackets 34, which are U-shaped, are provided with lugs 34a which are secured to lateral extensions 32a of plate 32 by screws 35 which pass through holes in lugs 34a and are threaded into plate 32. The legs of brackets 34 extend downwardly below table 10. Leaf springs 36, whose lower ends are fastened to the lower ends of brackets 34 by

screws 37, extend upwardly and their upper ends are fastened by screws 43 to the brackets 42 of a rectangular frame consisting of a pair of parallel bars 38 which are fastened by screws 41 to the ends of brackets 42. Bars 38 are provided on their lower edges with triangular notches 44 into which are inserted the upper edges of vanes 46 which are formed of suitable flexible material such as thin sheet metal. The lower edges of vanes 46 are anchored in slots 47 (Fig. 1) formed in the upper face of plate 32. The slots 47 closely fit the lower edges of vanes 46, but are shown somewhat exaggerated in size for better visibility. A bracket 48 secured by screws 49 to the bottom of a lateral extension 30' of the plate 30 (Fig. 3) is provided with a boss 50 in which is supported a cam shaft 51 carrying a pulley 52 driven by a belt 54. The hub 55 of a barrel cam 56 is fastened on the portion of shaft 51 adjacent the inner side of bracket 48. Cam 56 is provided with a track 57 which engages a cam follower 58 secured in the lower end of a cam lever 60. The lower end of cam lever 60 is split and the cam follower 58 is retained therein by a screw 61 threaded into the split portions of the lever. Lever 60 is clamped on the end of a shaft 62 projecting from a pedestal 63 wherein shaft 62 is supported (Fig. 4). Pedestal 63 is secured to a lateral extension 30'a of plate 30. To the other end of shaft 62 is fastened an arm 64 which is connected by a pin 65 to a bracket 66. To bracket 66 is secured one end of an arm 67 which is fastened at its other end by screws 68 to the bottom of one of the brackets 42. A tension spring 70 is connected to a stud 71 secured in the other bracket 42 and passes through a hole 72 in block 12 and is anchored to a strap 74 secured to block 12, to maintain cam roller 58 against the track 57 of cam 56.

Thus the bars 38 are reciprocated from cam lever 60 to flex the vanes 46 and thereby insure feeding of the cigarettes downwardly from the portion of the hopper above the upper edges of vanes 46 into the passageways between the vanes. A finger 76, whose inner end is located between the pedestal 63 and the adjoining bracket 34, has a longitudinal slot 76a through which pass screws 77 which are threaded into the top of the lateral extension 30'a of the plate 30. The outer end of finger 76 is upturned and projects sufficiently from between block 14 and bracket 34, so that it may be pushed inwardly to the right in Fig. 3 to insert its inner end under the lug 78 on the upper end of cam lever 60 and thereby prevent vibration of vanes 46.

At the bottom of the passageways between vanes 46 a layer or row of cigarettes consisting of 10 cigarettes is formed to be ejected into the cigarette box. On strips 19 are hinged frames 78 and 79 respectively (Fig. 2), which are provided with openings (not shown) covered with a sheet of suitable transparent material, to permit inspection of the cigarettes in the passageways between vanes 46. It should be noted that the frame 78 and its hinge are omitted from Fig. 1.

For ejecting the lowermost layer of cigarettes from the passageways between vanes 46 there is provided a horizontal slide 80 which is slidably mounted in a box-shaped frame 82 formed of sheet metal and provided with lugs 83 secured to plate 30 by screws 84. The forward end of frame 82 is open and the forward end of slide 80 normally projects from the same. The forward end of slide 80 is provided with longitudinal slots 75

aligned with vanes 46 to provide a series of fingers 85 which enter the passageways between vanes 46 and eject the lowermost layer of cigarettes therefrom. The vanes 46 may be provided with integral lugs 86 on the lower portions of their rear vertical edges. Lugs 86 extend between the tips of fingers 85 when the slide 80 is retracted to its rearmost position shown in Figs. 2 and 3. Thus the engagement of lugs 86 with the tips of fingers 85 prevents vibration of the portions of the vanes 46 behind the lugs, whereby the fingers 85 may be inserted into the proper passageways between the vanes when slide 80 moves forwardly. The portions of vanes 46 above lugs 86 will be vibrated continuously unless finger 76 is inserted under the lug 78 of cam lever 60.

A bracket 87 fastened to slide 80 carries a shaft 88 which is connected by a link 89 to a cam lever 91 fulcrumed on a bracket 93 secured to the bottom of plate 30. Cam lever 91 is provided with a cam roller 95 which is urged toward the periphery of a plate cam 96 mounted on shaft 51, by a tension spring 97 connected at one end to a stud on lever 91 and suitably anchored at its other end to a member 97a supported by bracket 93.

A U-shaped block 98 is fastened to cam lever 91 by screws 99. A trigger 100, which normally engages the forward edge of block 98 and thereby prevents the forward movement of lever 91, is pivoted on a bracket 101 fastened to the bottom of plate 30. The lower end of trigger 100 is provided with a counter-bored hole through which passes a rod 103. A collar 105 is clamped on rod 103, and a tension spring 107 connected to rod 103 and anchored on a stud 109 secured in the bottom of table 10 urges rod 103 rearwardly and thereby causes the collar 105 to swing trigger 100 upwardly on its pivot until its upper end is disposed in the path of block 98 on cam lever 91. Thus, when trigger 100 engages block 98, movement of the cam lever 91 is prevented until trigger 100 is disengaged from block 98 in a manner which will now be described. Rod 103 may also be provided with a compression spring 111 seated against a collar 113 on rod 103 and maintaining the lower end of trigger 100 against collar 105. In a bracket 120, which is fastened to the bottom of the forward end of plate 30, is supported a shaft 121. Both ends of shaft 121 project from bracket 120 and on one end of shaft 121 is supported a feeler or finger 122. The lower end of feeler 122 is split and clamped on shaft 121 by a screw 123. A lever 124, whose upper end is split and clamped on the other projecting end of shaft 121 by a screw 125 is connected by a pin 126 to the rod 103. When finger 122 is displaced rearwardly by a cigarette box B placed on a stationary support 128 in position to receive a layer of cigarettes ejected from the passageways between vanes 46, the lever 124 is swung forwardly until it engages a stud 127 on bracket 120. Thus the rod 103 will be displaced forwardly against the resistance of spring 107. However the trigger 100 will remain in the upwardly swung position and will not be disengaged from the block 98 on cam lever 91 until the cam lever 91 has assumed its rearmost position shown in Fig. 2, because the spring 111 on rod 103 is much weaker than the spring 97 connected to lever 91. Therefore the spring 111 cannot swing the trigger 100 downwardly until the cam 96 has displaced the lever 91 to its rearmost position wherein block 98 is retracted out of engagement with trigger

100. The trigger will then swing downwardly and the slide 80 will be moved forwardly with lever 91 as cam 96 revolves, whereby the fingers 85 will eject the layer of cigarettes into box B. Then when the cam lever 91 is against returned to its rearmost position the trigger will be swung upwardly in front of the block 98 by the spring 107. Since the block 98 is slightly spaced from the trigger 100 at the rearmost position of lever 91, the block will reengage the trigger when lever 91 moves forward slightly from its rearmost position. Then the slide 80 will not move until the feeler 122 is tripped a second time by the same package, to deliver a second layer of cigarettes therein, or by a different package. The cigarettes ejected from the passage-ways between vanes 46 are guided into the cigarette box between tapered strips 129 fastened to the top of plate 32.

What is claimed is:

1. In a cigarette feed, the combination with a hopper adapted to contain a supply of cigarettes, of a series of spaced vanes extending downwardly from the bottom of the hopper to provide a series of passage-ways wherein cigarettes are guided downwardly from the bottom of the hopper, a reciprocable ejector arranged to engage and eject cigarettes from the lower ends of said passage-ways, a movable feeler arranged in front of said vanes and adapted to be displaced by a cigarette box properly positioned to receive the cigarettes delivered from the passageways by the ejector, a member mounted for to and fro motion and connected to said ejector, means for imparting to and fro motion to said member, a releasable device normally holding said member against motion, and connections between said feeler and said device for releasing said device and permitting said member to move said ejector and thereby eject the cigarettes upon movement of said feeler by said box.

2. In a cigarette feed, the combination with a hopper adapted to contain a supply of cigarettes, of a series of spaced members extending downwardly from the bottom of the hopper to provide a series of passage-ways wherein cigarettes are guided downwardly from the bottom of the hopper, an ejector arranged to engage and eject cigarettes from the lower end of said passage-ways, a movable feeler arranged in front of said members and adapted to be displaced by a cigarette box properly positioned to receive the cigarettes delivered from the passage-ways by the ejector, and mechanism which is set into operation by the displacement of the feeler by a cigarette box positioned to receive the ejected cigarettes, for actuating said ejector to deliver the cigarettes from said passage-ways into said box, said mechanism including a lever connected to said ejector, a spring normally urging said lever toward said passage-ways to cause said ejector to deliver cigarettes from the lower ends of the passage-ways, and a latch normally engaging and preventing movement of said lever and connected to said feeler and adapted to be disengaged from said lever when the feeler is displaced by a cigarette box, to permit the cigarettes to be delivered into the box.

3. In a cigarette feed, the combination with a hopper adapted to contain a supply of cigarettes, of a series of spaced members extending downwardly from the bottom of the hopper to provide a series of passage-ways wherein cigarettes are guided downwardly from the bottom of the hopper, an ejector arranged to engage and eject cigarettes from the lower ends of said passage-ways,

a movable feeler arranged in front of said members and adapted to be displaced by a cigarette box properly positioned to receive the cigarettes delivered from the passage-ways by the ejector, and mechanism which is set into operation by the displacement of the feeler by a cigarette box positioned to receive the ejected cigarettes, for actuating said ejector to deliver the cigarettes from said passage-ways into said box, said mechanism including a cam lever connected to said ejector, a continuously revolving cam, a cam roller on said lever engaging said cam, a spring arranged to urge the cam lever toward the passage-ways and thereby maintain said roller against said cam, said cam having a contour permitting sufficient movement of said lever to permit the ejector to deliver the cigarettes from said passage-ways, and a latch normally engaging and preventing movement of said cam lever, said latch being connected to said feeler and adapted to be disengaged from said cam lever when the feeler is displaced by a cigarette box whereby the ejector will deliver cigarettes from said hopper into the cigarette box.

4. In a cigarette packaging machine, the combination with a hopper adapted to contain a supply of cigarettes and having a bottom provided with an opening, of a series of vanes extending downwardly from the opening in the hopper bottom to provide a series of passage-ways wherein cigarettes are guided downwardly from the bottom of the hopper, an ejector arranged to move forwardly to engage and eject cigarettes from the lower ends of said passage-ways, and means for flexing said vanes to cause the cigarettes to enter the upper ends of said passage-ways and thus be guided downwardly to the lower ends thereof, said ejector having longitudinal slots providing fingers adapted to enter the lower ends of said passage-ways to eject the cigarettes therefrom, and said vanes having extensions arranged to be positioned in said slots when the ejector fingers are withdrawn from said passage-ways to guide said fingers into the passage-ways when the ejector moves forwardly.

5. In a cigarette packaging machine, the combination with a hopper adapted to contain a supply of cigarettes and having a stationary bottom provided with an opening, of a series of spaced flexible vanes extending downwardly from the opening in the bottom of the hopper to provide a series of passage-ways wherein cigarettes are guided downwardly from the bottom of the hopper, an ejector arranged to engage and eject cigarettes from the lower ends of said passage-ways, means for flexing said vanes to cause the cigarettes to enter the upper ends of said passage-ways and thus be guided downwardly to the lower ends thereof, said means including a frame engaging the upper ends of said vanes, a cam lever connected to said frame, a cam for oscillating said lever to flex said vanes, and a device for interrupting the flexing of said vanes, said device including a manually operable detent movable into position to prevent the oscillation of said lever and thereby interrupt the flexing of said vanes.

6. In a cigarette feed, the combination with means for delivering a row of cigarettes into a predetermined position for delivery to a cigarette box, of an ejector arranged to engage and eject said row of cigarettes from said predetermined position into a cigarette box, a feeler adapted to be displaced when a cigarette box is properly positioned to receive the row of cigarettes ejected from said means by said ejector,

and mechanism which is set into operation by displacement of said feeler for actuating said ejector to deliver said row of cigarettes from said means into said box, said mechanism including a cam lever connected to said ejector, a continuously revolving cam, a cam roller on said lever engaging said cam, a spring arranged to urge the cam lever and ejector toward said means, said cam having a contour permitting sufficient movement of said lever to permit the ejector to eject said row of cigarettes from said means into said box, a rod connected to said feeler, a pivoted latch having an opening in its lower end through which said rod passes, a collar secured on said rod in front of said lower end of said latch, a tension spring connected to said rod and serving to press said collar against the lower end of said latch to maintain the upper end of the latch in the path of said cam lever and thereby prevent the operation of said ejector, a compression spring mounted on said rod and positioned behind the lower end of said latch to urge the same toward said collar, said cam operating to displace said lever rearwardly to a position wherein said lever is out of contact with the upper end of said latch whereby said latch will swing downwardly out of the path of said lever if said feeler has been previously displaced whereby the ejector will be actuated.

7. In a cigarette packaging machine, the combination with a hopper adapted to contain a supply of cigarettes and having a stationary bottom provided with an opening, of a series of spaced resilient vanes extending downwardly from the opening in the bottom of the hopper to provide a series of passage-ways wherein cigarettes are

10

15

20

25
